UNITED STATES PATENT OFFICE.

CLINTON H. SEITZ, OF SHREWSBURY, PENNSYLVANIA.

AUTOMATIC AIR-BRAKE COUPLING.

SPECIFICATION forming part of Letters Patent No. 701,628, dated June 3, 1902.

Application filed December 14, 1901. Serial No. 85,931. (No model.)

To all whom it may concern:

Be it known that I, CLINTON H. SEITZ, a citizen of the United States, residing at Shrewsbury, in the county of York and State of Pennsylvania, have invented a new and useful Automatic Air-Brake Coupler, of which the following is a specification.

This invention is an improved construction of coupling particularly adapted for automatically connecting steam or air pipes used in connection with railway-cars and automatically coupled at the same time the cars are coupled.

The object of the invention is to provide a coupling which shall be simple and efficient in construction; and with this object in view the invention consists in the novel features of construction and combination hereinafter fully described, and pointed out in the claims.

In the drawings forming a part of this specification, Figure 1 is a perspective view showing the application of my invention. Fig. 2 is a top plan view illustrating two couplers connected. Fig. 3 is a longitudinal sectional view of one of the couplers. Fig. 4 is a detail perspective view showing the head of the said coupler, and Fig. 5 is a transverse section on the line 5-5 of Fig. 3.

In carrying out my invention I employ a cylinder A, which is connected at its rear end to air or steam pipe A'. The inner cylinder of tube B slides longitudinally within the cylinder A, a packing C, of suitable material, being interposed between the tube B and the forward end of the cylinder A, said packing being held in place by means of flanges C' and C'', projecting inwardly from the cylinder A. The rear end of the cylinder A has an opening D produced therein, which opening is normally closed by means of the cone-shaped valve E, the stem E' thereof being rigidly connected to a cross-bar E'', carried at the rear end of the tube B, and in order to close the valve E, I employ a coil-spring F, which bears at its rear end against the rear end of the cylinder and at its forward end upon a collar F', which is rigidly attached to the exterior of the tube B adjacent to its rear end, the forward portion of the spring surrounding the rear portion of the tube B, as most clearly shown, said spring thereby serving to project the tube B outwardly and main-

tain the valve E in a closed position at the rear end of the cylinder A.

At the forward end of the tube B is arranged a coupling-head G, having two forwardly-projecting wings G', and these wings are arranged upon the top and bottom of one head and upon the opposite sides of the opposing head, so that when the heads are brought together, as shown in Fig. 2, the side wings of one head will pass between the top and bottom of the opposing head, and thereby complete the coupling, the flat faces of heads contacting with each other, and in practice I prefer to arrange rubber packing-rings H upon the forward faces of the heads, thereby insuring a perfectly-tight joint and also relieving the forward faces of the heads from any sudden jar or pressure. Each head is also provided with a forwardly-projecting guard I, which is essentially in the form of a half bell or funnel, as most clearly shown in Figs. 1 and 2, said guard being connected to the tube B at a point in the rear of the head H, as most clearly shown in Fig. 3. These guards flare outwardly, and thereby serve to guide the heads toward each other, so that the coupling is facilitated. When the heads are brought together and coupled, each tube B is of course forced inwardly into the cylinder A, and said inward movement of the tube B opens the valve E, thereby permitting air or steam to pass into the cylinder A and through the tubes B, said tubes being in communication, thereby establishing a connection between the steam or air pipes of the train.

It will thus be seen that I provide an exceedingly cheap, simple, and efficient automatic coupler for air or steam pipes.

In order to prevent the tube B turning within the cylinder A, I provide a spline or rib F'' upon the interior of the cylinder A, which spline works through a notch or recess F'', produced in the collar F', encircling the tube B. A stout spring G'' is arranged between the end of the tube A and the coupling-head G, said spring serving to hold the coupling-head in its proper position. It will also be understood that the said coupling-head can have a limited rotary movement, thereby permitting two heads to move accurately into engagement with each other.

Having thus fully described my invention,

what I claim as new, and desire to secure by Letters Patent, is—

1. In a device of the kind described, the combination with the tubes of the coupling-heads arranged thereon, one coupling-head having the forwardly-projecting wings at the upper and lower sides, the opposing head having the forwardly-projecting wings at its opposite sides, and the forwardly-projecting and outwardly-flaring guard arranged at the side of each coupling-head, substantially as set forth.

2. In a device of the kind described, the combination with a cylinder having an opening in its rear end, of a tube movable longitudinally in the said cylinder and projecting forwardly from the forward end of the said cylinder, the packing arranged at the forward end of the cylinder and between the

20 said cylinder and tube, the flanges for holding the packing in place, the valve for closing the opening at the rear end of the cylinder, said valve being rigidly connected to the rear end of the tube, a coiled spring arranged within the cylinder and surrounding the rear 25 portion of the tube, a collar arranged upon the said tube and against which the forward end of the spring bears, the coupling-head arranged upon the forward end of the tube and having the forwardly-projecting wings 30 arranged at diametrically opposite points and the guard arranged at the side of the coupling-head, substantially as described.

CLINTON H. SEITZ.
